UNITED STATES PATENT OFFICE

RANEY J. ROBERTS, OF DETROIT, MICHIGAN

OIL BURNER

Application filed November 2, 1927. Serial No. 230,468.

The present invention pertains to a novel oil burner of the general type used for heating purposes in habitable buildings.

The principal object of the invention is to provide a device of this character equipped with a dependable pilot light. Still another object is to provide an oil drainage system which will function promptly and effectively as soon as the oil ceases to ignite.

10 In the accomplishment of these objects I provide one or more branches which carry the oil to the bowl. In each branch is mounted a wick which has one end extending into the bowl. The wick is either spaced from 15 the inner wall of the branch or formed with an axial passage, or both, in order to permit direct flow of oil to the bowl, rather than by capillary action entirely, when the device is functioning in the normal manner. When 20 the supply of oil is cut off for extinguishing the burner, a considerable quantity of oil remains in the branch which contains the wick. This residue rises in the wick by capillary action and burns at the end which is positioned within the bowl, thereby maintaining 25 a pilot light.

For the purpose of proper distribution of the oil around the bowl, the latter is formed with concentric grooves into which the wicks 30 are extended. The oil issuing from the wicks is thus promptly distributed in a circular path around the center of the bowl. A drain pipe leads from a lower level of the bowl so that the oil will not be permitted to accumulate in the burner in case the same should 35 accidentally become extinguished.

Still another object of the invention is to provide a whirling means for the air which enters the burner in order that such air may 40 be intimately mixed with the oil.

The invention is fully disclosed by way of example in the following description and in the accompanying drawing, in which—

Figure 1 is a vertical section of a burner 45 constructed according to the invention;

Fig. 2 is a bottom plan view of the distributor cap;

Fig. 3 is a fragmentary vertical section thereof, showing one of the vanes in elevation;

Fig. 4 is a plan view of the burner; Fig. 5 is a section on the line 5—5 of Figure 4;

Fig. 6 is a section on the line 6—6 of Figure 4; and

Fig. 7 is a vertical section of one of the supporting legs.

Reference to these views will now be made by use of like characters which are employed to designate corresponding parts throughout.

The burner rests upon a base 1 and is supported thereon by extensible legs of the character shown in Figures 1 and 7. Two such legs are provided for engaging the burner at diametrically opposite points thereof. 65 Each such leg includes a lower section 2 having a foot 3 secured to the base by a bolt 4. The bolt is preferably received in a slot 5 cut in the foot for the purpose of rapid assembly. Each leg also includes an adjustable section 6 having its lower end secured to the section 2 by a bolt 7 received in a slot 8 cut longitudinally in the section 2. A bowl base 9 is secured to the upper ends of the members 6 by bolts 10, and the upper ends of the 75 members 6 are preferably slotted as at 11 for rapid assembly of the bolts 10 thereto as at the slot 5 of the foot 3.

The member 9 has a central boss 12 which forms the air inlet 13. The lower edge of the 80 boss is rabbeted externally at 14 for the attachment of an air supply pipe 15 leading from a suitable source such as a blower. The floor 16 of the base member 9 slopes downwardly towards the boss 12 as clearly shown in Figure 1 and is formed with a circular groove 17 which is concentric with the inlet 13. To the upper end of the boss 12 is secured an air distributor cap 18 having its wall comprised of spaced curved vanes 19 which form between them passages 20 leading from the interior of the cap to the bowl in a direction which somewhat merges into a circular path, whereby the air issuing through these spaces 85 is given a whirling motion. The lower ends of the vanes are notched as at 19' for receiving the upper end of the boss 12 in such a manner that the cap is centered thereon. The 90 bowl is completed by a wall member 21 se- 100

cured to the outer edge of the base member 9 and rested thereon.

The oil is delivered to the bowl through a supply pipe 22 having two branches 23 entering the bowl at diametrically opposite points thereof and preferably at the groove 17. The branches stand vertically as shown in Figure 5 and contain each a wick 24. The wick is spaced as at 25 from the inner wall of 10 the branch and is also formed with an axial passage 26 whereby the oil may flow directly through the branch notwithstanding the presence of the wick therein. Either the space 25 or the passage 26 may be dispensed 15 with in keeping with this object. The wicks have their upper ends disposed within the bowl, and due to the fact that the inlet branches enter at the groove 17, these ends lie substantially in the grooves. Finally, a 20 drain pipe 27 leads from the floor 16 of the base member 9.

In the normal operation of the device oil is caused to flow directly through the space 25 and passage 26 through which it is discharged 25 into the circular groove 17 and distributed therein. Due to this distribution of the oil around the center of the burner, the combustion is spread uniformly throughout the device rather than concentrated in any given re- 30 stricted area. The air which is forced through the pipe 15 is imparted a whirling motion between the vanes 19 in the manner already described, whereby a thorough commingling of air and oil is effected. When the 35 burner is extinguished, there remains a quantity of oil standing in the branches 23 and absorbed in the wicks 24. This residue continues to burn at the upper ends of the wicks, and the small flames produced in this man- 40 ner constitute pilot lights. When the supply of oil is resumed it will be promptly directed by the groove 17 to these burning ends, and 45 combustion will promptly follow. Flooding of the burner through interrupted or im- proper combustion is avoided by drainage through the pipe 27.

Although a specific embodiment of the invention has been illustrated and described, it will be understood that various alterations in 50 the details of construction may be made without departing from the scope of the invention as indicated by the appended claims.

What I claim is:—

1. In an oil burner, a bowl, an air pipe lead- 55 ing to the center thereof, and a distributor cap mounted on the outlet end of said pipe, said cap having a lateral wall consisting of spaced vanes and having a top piece covering said lateral wall.

60 2. In an oil burner, a bowl, an air pipe leading to the center thereof, and a distributor cap mounted on the outlet end of said pipe, said cap having a lateral wall consisting of spaced curved vanes forming spaces 65 which provide paths from the interior of the

cap to the bowl in the general direction of the periphery of the bowl, said cap having also a top piece covering said lateral wall.

3. In an oil burner, a bowl, an air pipe leading to the center thereof, and a distributor cap mounted on the outlet end of said pipe, 70 said cap having a lateral wall consisting of spaced vanes adapted to whirl air issuing through the spaces therebetween.

In testimony whereof I affix my signature. 75
RANEY J. ROBERTS.
